United States Patent Office

Des. 195,014

Patented Apr. 9, 1963

195,014

AIRPLANE

Frank E. Guadagnini, Long Beach, John W. Patierno,
Los Alamitos, Haig Asdurian and Don M. Heinze, Los
Angeles, and Eddie J. Schwarz, Inglewood, Calif., as-
signors to Northrop Corporation, Beverly Hills, Calif.,
a corporation of California

Filed July 20, 1961, Ser. No. 65,998

Term of patent 14 years

(Cl. D71—1)

FIGURE 1 is a top perspective view of the aircraft embodying our new design.

FIGURE 2 is a front elevation thereof.

FIGURE 3 is a top plan view of the aircraft.

FIGURE 4 is a side elevation thereof, the side opposite that shown in FIGURE 4 is a mirror image of the side shown.

The dominant features of our design reside in the portions shown in full lines.

We claim:

The ornamental design for an aircraft, substantially as shown and described.
